Inventor:

UNITED STATES PATENT OFFICE.

PRATT C. MORRIS, OF THOMASVILLE, GEORGIA, ASSIGNOR TO CHARLES W. COOPER, OF THOMASVILLE, GEORGIA.

COIL-BOX PROTECTOR.

1,419,120.

Specification of Letters Patent. Patented June 6, 1922.

Application filed May 16, 1918. Serial No. 234,978.

To all whom it may concern:

Be it known that I, PRATT C. MORRIS, a citizen of the United States, residing at Thomasville, in the county of Thomas and State of Georgia, have invented certain new and useful Improvements in Coil-Box Protectors; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to a protector for a coil box, more particularly of automobiles.

It has for its object to provide means for keeping the coil box dry or free from wet or dampness resulting from exposure to weather conditions or washing the vehicle or automobile. The coil box, especially in the Ford type of car, is attached to or supported from the dash-board of the car, which being exposed becomes wet or damp from exposure in wet weather and also in washing the car, and this moisture being communicated to the coils of the box frequently causes a short circuit and for the time being puts the car out of commission. With the view of protecting the coil box and preventing the short circuiting mentioned, the invention consists in the features hereinafter described and then sought to be clearly defined by the claims, reference being had to the accompanying drawing forming a part hereof, and in which—

Figure 1 is a side view of the forward portion of an automobile of the Ford type, with a portion broken away and showing the dash-board and the protector in vertical section;

Figure 2 is a front view of the protector or shield;

Figure 3 a vertical section through the protector on the line 3—3 of Figure 2, looking in the direction of the arrows.

In the drawing the numeral 1 designates a portion of an automobile and 2 the dash-board in a car of the Ford type. 4 designates the coil-box cover or case in which is contained the coil-box from which extend the proclain covered terminals or binding posts 5 for connection therewith of the conductors 6, all as usual in cars of the type mentioned. The coil box protector or shield

is designated by the numeral 7. It is made of sheet metal, or other suitable material, and formed with forwardly projecting nipples or tubes 8, corresponding in number to the terminals or binding posts of the coil box, and extending through a corresponding number of openings in the dash-board. The protector lies between the dash-board and the coil box as illustrated in Figure 1 and will be bolted to the dash-board by bolts 60 (not shown) passing through the dash-board and holes 9 made in the protector, and the terminals or binding posts of the coil-box will pass through the nipples 8 of the protector and have the conductors connected 70 thereto as shown in Figure 1. The upper end 10 of the protector is curved backwardly above the top or cover to the coil-box as illustrated in Figure 1 so that any water entering through the automobile front portion 75 at the top of the dash-board will be caught by the curved or overhanging top of the protector and directed down the front face of the protector away from the coil-box. This feature of the device forms the subject matter of a division of this application filed October 6, 1919, and which has eventuated in Patent No. 1338581 dated April 27, 1920. The protector formed and applied as described effectively shields the coil box and 80 its terminals from water that may enter about the dash-board and also against the dampness or moisture that may be absorbed or trickle down the dash-board and thus the short circuiting heretofore occurring in coil 85 boxes of automobiles is prevented.

I have described the preferred construction of the protector but changes in details may be made and essentials of the invention retained.

Having described my invention and set forth its merits, what I claim is:

1. In combination with the coil-box and dash-board of a motor vehicle, a protector applied to the face of the coil-box between it 100 and the dash-board and formed with nipples fitting corresponding openings in the dash-board and adapted to receive the terminals or binding posts of the coil-box.

2. The combination of a dash having apertures, a coil box having binding posts extending through the apertures, and a protector for the binding posts comprising a plate secured to the dash between the same and the coil box and having guards extend-

95

110

ing through the apertures of the dash in a position over the binding posts.

3. A protector of the class described comprising a supporting plate having a plurality of apertures, and a guard member at each aperture, said guard members extending all from one face of the plate.

In testimony whereof I affix my signature in presence of two witnesses.

PRATT C. MORRIS.
